CLAIM

The ornamental design of a paper towel holder, as shown
and described.

DESCRIPTION

FIG. 1 is a side elevational view of the paper towel holder
in an orientation that exists when no paper towels are on the
holder;

FIG. 2 is a side elevational view similar to FIG. 1, but
showing the orientation of the paper towel holder when a roll
of paper towels is mounted thereon;

FIG. 3 is a front elevational view of the paper towel holder
shown in FIG. 1;

FIG. 4 is a top plan view thereof;

FIG. 5 is a rear elevational view thereof; and,

FIG. 6 is a bottom plan view thereof.
